COMBINED MOBILE BAR AND STORAGE UNIT

Carter Clifford Hoffmann, Lake Forest, and Toivo W. Luoma, Waukegan, Ill., assignors to Carter-Hoffmann Corp.

Filed May 30, 1972, Ser. No. 258,213

Term of patent 14 years

Int. Cl. D6—04

U.S. Cl. D6—144

Fig. 1.

Fig. 2.

Fig. 3.

FIG. 1 is a rear perspective view of a combined mobile bar and storage unit showing our new design with the storage unit being omitted for clarity of illustration;

FIG. 2 is a front perspective view thereof;

FIG. 3 is a top plan view;

FIG. 4 is a rear perspective view of the combined mobile bar and storage unit with the storage unit in place; and

FIG. 5 is a side elevational view from the left of FIG. 4.

We claim:

The ornamental design for a combined mobile bar and storage unit, substantially as shown and described.
